United States Patent

Des. 237,736
Patented Nov. 18, 1975

237,736

CANDLE HOLDER

Clark L. Lofgren, Raynham, Mass., assignor to Reed and Barton Corporation, Taunton, Mass.

Filed Feb. 19, 1974, Ser. No. 443,393

Term of patent 14 years

Int. Cl. D26—01

U.S. Cl. D48—2

FIG. 1

FIG. 2

FIG. 3

FIG. 4

FIG. 1 is a perspective view of a candle holder showing my new design;

FIG. 2 is a top plan view thereof;

FIG. 3 is a bottom view thereof; and

FIG. 4 is a side elevational view thereof.

I claim:

The ornamental design for a candle holder, substantially as shown.
